(57) **CLAIM**

The ornamental design for a ball code lock, as shown and described.

DESCRIPTION

FIG. 1 is a front, top perspective view of a ball code lock, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the ball code lock, which form no part of the claimed design.

1 Claim, 8 Drawing Sheets
